SPINAL BRACE

William L. Bell, Oakland, Calif.

Application February 10, 1936, Serial No. 63,052

5 Claims. (Cl. 128—78)

This invention relates to improvements in spinal braces and more particularly to spinal bridges.

An object of the invention is to apply corrective forces to the lumbar region of the human spine to assist in maintaining the normal antero-posterior equilibrium of the body.

Another object is to reinforce the supporting power of the spine without interfering with its normal articulated freedom of motion.

Another object is to accomplish and maintain the natural longitudinal alinement of the spinal vertebrae without unduly limiting freedom of spinal motion and respiration.

15 A further object is to bridge the curve of the lumbar segment of the spine from the sacrum to the dorsal segment.

Other objects and advantages will appear as the description progresses.

20 This invention should not be confused with the corset type of brace and those corrective means which enclose the body and indirectly hold the spine in an arbitrary position with a limited freedom of action.

25 The three point contact of the present invention, touches the spine at the sacral and the dorsal areas and the frontal abdominal region. Between these separated points the spine has three degrees of freedom: forward, backward, lateral and rotational. The sacral base contact

30 resiliently tips the sacrum upward and backward, by means of the leverage exerted between it and the dorsal and abdominal contacts. Thus flexing the lumbar region rearwardly automatically inclines the head backwardly, which flexes the dorsal region forwardly, pulls the chin back and throws the whole spinal column more in line with the natural center of gravity, from the head to the ankles of the skeletal frame. This effect can-

35 not be accomplished by any form of brace which renders any given section of the spine immobile. Balance must be maintained in both the dynamic and static state. Proper alinement of the spinal vertebrae insures a more uniform distribution of 40 weight on the intervertebral discs, insuring greater static stability, dynamic flexibility and nerve freedom.

The present invention reduces fatigue in action by bridging the curve in the lumbar segment and 45 transmitting the strain from the dorsal region directly to the posterior surface of the sacrum, particularly indicated in "sway back."

In this specification and the accompanying drawings the invention is disclosed in its preferred form. It is to be understood, however,

that it is not limited to this specific form because it may be embodied in modifications within the purview of the claims following the description.

In the two sheets of drawings:

Fig. 1 is a side view of the invention as applied 5 to the human body.

Fig. 2 is an enlarged diagrammatic detail view of the same in vertical section, showing in dotted lines the positions of the spinal and abdominal 10 region in relation to the apparatus.

Fig. 3 is an enlarged detail in front elevation of the abdominal pad.

Fig. 4 is a rear elevation of the spinal bridge, with the covering partially removed to disclose 15 the inner structure.

Fig. 5 is a vertical section of the same.

Fig. 6 is a diagrammatic plan view from above indicating the clearance between the bridge and the back of the wearer.

In detail the construction illustrated in the 20 drawings, referring first to Fig. 4, comprises the vertical lumbar bridge 1, extending from the sacrum A at the base end 2, upward to the dorsal region B at the upper end 3. This bridge is preferably composed of aluminum alloy or any suitable material that will combine the required 25 flexible strength with minimal weight and bulk.

This bridge 1—2—3 is curved inwardly throughout its length, with a radius slightly greater than the curve of the lumbar segment C of the spine. 30 The pivotal plates 4 and 5 are hinged at 6 and 7 to the respective ends 2 and 3 of the bridge 1. The cushion pads 8 and 9 are removably attached to their respective plates 4 and 5. The pads are composed of block felt or any other suitable material and are easily removable as required. These pads conform to the angles of the spine and the hinges 6 and 7 permit the necessary free back and forward movements of the spine. The greater radius of the bridge leaves the space C', 40 see Fig. 2, to clear the spinal processes on the intervening vertebrae, as the spine bends or rotates between the points A and B.

The bridge 1 has the lateral extensions 10 and 45 11 which form in effect a cross brace about equal in length to the length of the bridge 1 and adapted to extend laterally across the small of the back beneath the lower ribs. A cross brace rigidly attached to the bridge 1 can be substituted for 50 the extensions 10 and 11 if desired. These extensions curve inwardly, but stand away from the back of the wearer to permit free flexing of the extensions 10 and 11 without side compression 55 of the abdominal walls and also permit free re-

spiratory space and ventilation between the brace and the body of the wearer, see Fig. 6.

The whole metallic body of the brace is enclosed within a sheath 12 of suitable fabric, such as canvas, cut to the outline and stitched around the margins. The pockets enclosing the pad portions at 8 and 9 have the loose flaps 13 and 14 respectively, adapted to be tucked beneath the cross portion 12' of the sheath, see Fig. 5. When 10 not being worn these flaps can be withdrawn to permit ventilation to dry out the pads.

The sheath has the three straps 15, 16 and 17 stitched thereto and extending across the back and beyond the extensions 10 and 11, see Fig. 1. 15 These straps engage the buckles 18, 19, 20, 21, 22 and 23 respectively, see also Fig. 3, at the sides of the abdominal pad 24 to form a belt encircling the wearer.

This abdominal pad 24 is formed of fabric similar to the sheath 12 and is reinforced by the flexible strips such as 25, to prevent the pad wrinkling horizontally. This pad lies over the umbilical region and may have the lower extension 26 adapted to extend under the curve of the 25 abdomen to act as an abdominal support where such necessity is indicated. This pad 24 is the third point or apex D of a triangle having its base at A—B, forming a three point suspension permitting the three degrees of freedom of motion of 30 the wearer as previously mentioned.

This invention is not a mechanical substitute for the human spine, as in the case of corsets, plaster casts and the like. It is a bridge for the fundamentally weak lumbar segment C, with 35 stresses applied from A—B to D, to scientifically urge proper posture in active persons engaged in the regular pursuit of productive living, sports, automobile driving or sitting for long periods. It is equally restful to a tired person sleeping or reclining by relieving the wedging action against the intervertebral discs, present in any prolonged hyper curvature of the spine in any direction, since such distortion of the discs in many instances causes traumatism in the complicated 40 nerve areas adjacent the vertebrae.

The lateral extensions 10 and 11 make it possible to reduce the overhang of a large abdomen

without compressing the viscera, because of the lateral freedom accomplished by these extensions 10 and 11, see Fig. 6. The strains of an excessive abdominal overhang aggravate the lumbar curve. In the present instance this load is transferred 5 to the strut bridge 1 and is borne by it from A to B, see Fig. 2. Thus retracting the abdomen contributes to a more normal center of gravity in the posture of the wearer and a more uniform distribution of muscular stresses in maintaining 10 equilibrium.

Having thus described this invention, what is claimed and desired to secure by Letters Patent is:

1. A spinal brace including a bridge having lateral extensions intermediate its ends, the upper 15 and lower ends of said bridge being arranged to engage the spine at the dorsal and the sacral regions respectively; and an abdominal belt attached to the lateral extensions of said bridge.

2. A spinal brace including a bridge adapted 20 to extend from the sacrum to the dorsal region of the spine and having lateral extensions intermediate its ends; yieldable plates on the opposite ends of said bridge respectively; and an abdominal belt attached to the side extensions of said 25 bridge.

3. A spinal brace including a bridge adapted to overlie the lumbar region of the back and spaced therefrom and having lateral extensions intermediate its ends; plates yieldably attached to the 30 upper and lower extensions of said bridge and adapted to rest upon the sacrum and the dorsal segment of the spine respectively; and an abdominal belt attached to the side extensions of said bridge.

4. A spinal brace including a bridge; hinge members on the opposite ends of said bridge; pads having their central portions attached to said hinge members respectively; and an abdominal belt attached to said bridge intermediate its ends. 40

5. A substantially rigid bridge approximately the length of the lumbar region of the human spine; pads flexibly attached to the opposite ends of the bridge respectively; and an abdominal belt attached to said bridge intermediate its ends. 45
